Primary Examiner — T. Chase Nelson
Assistant Examiner — Ania Aman(57) **CLAIM**The ornamental design for an impeller for superchargers, as
shown and described.**DESCRIPTION**FIG. 1 is a front elevational view of an impeller for
superchargers showing our new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof;
FIG. 7 is a front perspective view thereof; and,
FIG. 8 is a rear perspective view thereof.**1 Claim, 8 Drawing Sheets**| (56)	References Cited
